UNITED STATES PATENT OFFICE.

JOSEPH LE COMpte, OF OKLAHOMA, OKLAHOMA, ASSIGNOR, BY DIRECT AND MESNE ASSIGNMENTS, OF ONE-FOURTH TO A. D. MARBLE AND ONE-FOURTH TO SUSAN C. TAYLOR, OF OKLAHOMA, OKLAHOMA.

DAYLIGHT FILM-DEVELOPING APPARATUS.

No. 899,545.

Specification of Letters Patent.

Patented Sept. 29, 1908.

Application filed May 9, 1907. Serial No. 372,726.

To all whom it may concern:

Be it known that I, JOSEPH LE COMpte, a citizen of the United States, residing at Oklahoma city, in the county of Oklahoma, Oklahoma, have invented certain new and useful Improvements in Daylight Film - Developing Apparatus, of which the following is a specification.

My invention relates to daylight film developing apparatus, in which a film and developing tray compartment is provided, with viewing glasses in its walls by which to observe the process of developing; and a compartment for the developing liquid, which affords a kodak rest, all of which will herein-after be fully explained.

The objects of my invention are; first, to provide an apparatus which will avoid the necessity of constructing and maintaining a dark room for the development of films, such as are commonly used with kodaks; second, one with which a kodak can be conveniently carried; third, one having a place for carrying the developing liquid; fourth, one which requires no timing; fifth, one in which the developing process can be observed; sixth, one which can be used as well at night as by day. I accomplish these objects by the mechanism illustrated in the accompanying drawings, forming a part of this specification, in which—

Figure 1 is a rear perspective of my daylight developing apparatus; Fig. 2 is a front perspective of the same with portions broken away; Fig. 3 is a vertical section of the door; Fig. 4 is a central vertical sectional view of the apparatus; Fig. 5 is a front elevation of the apparatus as arranged for transportation.

Similar letters refer to similar parts in the several views.

Referring to the drawings, A designates the rectangular upright cabinet portion of the apparatus firmly secured to the base B; a cheap and efficient way of constructing the cabinet is to groove or channel the corner posts *a* and use thin sheets of wood for the walls with their vertical edges inserted in said grooves as in the present case, although metal may be used in the construction of the entire framework of the apparatus. The top C is firmly secured to the corner posts *a*, and has a carrying handle C' secured thereto.

Quite centrally located in the rear wall of the cabinet is a rectangular opening which constitutes the mouth of the light box E having a roof 1, a floor 2, a right wall 3, a left wall 4 and a rear or back wall *e*, being formed by securing said roof, floor and walls to the rear cabinet wall *a''* around said opening, see Figs. 1 and 4.

For supporting and actuating the film D the roller *b* is provided, having one of its horizontal journals *b'* passed through the rear wall *a''* of the cabinet and has a crank *c* for turning said roller, its other journal *c'* being supported by a vertical bar *c''* having its lower end secured to the end wall *e* of the light-box E, and, to afford access to the interior of the cabinet for the adjustment of the film D upon the roller *b*, the door H constituting the front wall of the cabinet has its lower end hinged to the base B, and has a knob or block *g* secured to its outer surface by which to pull the door open. See Fig. 2, which shows a portion of said door broken away to disclose interior parts.

To guard against the admission of light into the cabinet while adjusting the film D upon the roller *b*, the opaque bay-window-like hood *h* is provided, having its edges tacked or otherwise secured to the front of the cabinet, and having two hand-holes *h'* cut therein with their edges provided with elastic cord to closely contact the wrists and arms of the operator.

The cabinet base B is extended in one direction two or more times its width to form the floor J of the bottle-case, the cover of which consists of the vertical sides *i* and *i'* and the end *i''* secured to the roof *j* having one end hinged to two of the corner posts *a*, *a*; and for the convenient insertion and removal of the tray *d* a dovetail groove is cut longitudinally in the upper central portion of the base B extending nearly the entire length of the base and fitted therein is the sliding tray removing bar *k* having a pan *k'* resting upon and secured to its inner end forming a seat or rest for the tray *d*, see Figs. 1 and 4. The partition between the cabinet and the bottle-case being cut away necessitates some means for excluding the light during the process of inserting and removing the tray *d*, in which a dark curtain, or a sliding door

could be used, but a wing-door *l* as in the present case is deemed preferable, in which the upper edge of the door is pivoted to the corner posts *a*, *a*, one of its pivots being provided with a knob *m* by which to turn the lower edge of the said door up for the transit of the said tray, see Figs. 1 and 4.

To provide means for observing the development of the film *D* a ruby glass *F* is set in the left wall 4 of the light-box *E*, as viewed from the mouth of the box, and a ruby glass *G* is set in the adjacent wall *a'* of the cabinet, the film *D* in its movements passing between them, see Figs. 2 and 4.

15 To protect the hood *h* during dis-use and transportation the screw-eyes *n* are secured in the posts *a*, *a* and a cord *o* is run through them zigzag and tied, see Fig. 5. The bottle-case has capacity for two bottles *p* of developing liquid and water, the cover of the bottle-case affording a seat or rest for a kodak *K* which may be secured in place by a strap as *K'* Fig. 5, passed around the kodak and cabinet and buckled.

25 In operation, the kodak is removed; the views taken; the cord *o* untied and removed; the bottles *p* removed from the bottle-case; by means of the sliding tray-removing bar *k*, the tray *d* is withdrawn from the cabinet into the bottle-case, filled with developing liquid and returned; the film is taken from the kodak, tightly rolled, and both hands are thrust through the hand-holes *h'* in the hood *h*, the knob or block *q* is grasped and the top 35 of the door *H* is pulled forward and the film *D* is placed on the roller *b* and its ends are overlapped and pinned with a fine wood, or other non-corrosive pin; the door *H* being closed, by means of the crank *c* the roller *b* is 40 rotated carrying with it the film *D* which, in its movement passes continuously through the developing liquid in the tray *d*, see Figs. 1, 2 and 4. By the film *D* passing between the ruby glasses *F* and *G*, the operation and 45 development may be observed as indicated in Fig. 4; sufficient light being admitted into the light-box by day and a candle *f* being used by night to make the observations. When the proper stage of development is 50 reached the wing-door *l* is turned up, the wing-tray *d* drawn into the bottle-case, the wing-door closed, the cover of the bottle-case raised, the developing liquid returned to its bottle, a tray of water placed upon the pan *k'*, the said cover closed down, the door *l* raised, the tray of water slid into its place and a water bath given to the film *D* by rotating the roller *b*, a minute being sufficient 55 to prepare the film for removal, which is done 60 through the door *H*.

It will be understood that all joints must be sufficiently close to exclude the light from the cabinet, which may require some of the joints to be calked or lined.

65 While I have shown and described the pre-

ferred style, form and construction of my apparatus it will be understood that various changes within the scope of the claims may be made without departing from the spirit of my invention, which,

70

Having described, what I claim as new and desire to secure by Letters Patent, is—

1. In a daylight film developing apparatus; a rectangular upright cabinet body; a rectangular elongated base having a groove 75 in its upper surface and one of its ends forming a support for said cabinet or body; a slideable tray-bar fitted in said groove and having a tray-pan secured to its inner end being normally within said cabinet for the support and removal of a developing tray, a carrying handle secured to the top of the said cabinet for carrying the developing apparatus, substantially as described.

2. In a daylight-film developing apparatus; a rectangular upright cabinet; a base supporting and in one direction extending beyond said cabinet body and having a slideable tray-bar fitted in its upper surface; a bottle-case having its roof hinged to said cabinet above said base, said base constituting its floor for the purpose of carrying the liquids used in developing the films, as set forth.

3. In a daylight film developing apparatus; a rectangular upright cabinet secured to a base and having an opening in one of its walls; a light-box within and secured to one of the side walls of the cabinet the said opening being the mouth of the light box; a ruby glass set in one of the side walls of said light box to aid in observing the development of the film, substantially as described.

4. In a daylight film developing apparatus; a rectangular upright cabinet having a base extending in one direction with a tray removing bar in its upper portion; a light-box within said cabinet secured to one of its walls said wall having an opening cut there-through as a mouth of said box to admit light therein, and having a ruby glass in one of its walls; a film actuating roller within said cabinet and having one of its journals extending through one of the walls of the cabinet above said light-box and having a crank attached to said journal for rotating the roller and the film which it carries, as described.

5. In a daylight film developing apparatus; a rectangular upright cabinet having a 120 bottle-case with a floor having a slideable tray-removing-bar fitted therein; a light-box within said cabinet secured to one of its sides with a light admitting opening therein; a ruby glass set in one of the walls of said 125 light-box to afford and control the light during the process of the film developing; a ruby glass set in one of the walls of the said cabinet adjacent the ruby glass in the wall of said light-box; a film carrying and actuating 130

roller secured within said cabinet with means for rotating the same, for the purposes specified.

6. In a daylight film developing apparatus; a rectangular upright cabinet; a rectangular elongated base one end of which supports the said cabinet and forms the floor thereof; a bottle-case having its cover hinged to one of the sides of said cabinet and having a portion of said base form the floor of said bottle-case; a tray-inserting and removing slide attached to said base; a door constituting one of the sides of said cabinet to afford access thereto; a knob or block secured to said door by which to open the same; a light excluding hood attached to the cabinet around said door, substantially as described.

7. In a daylight film developing apparatus; a rectangular upright cabinet, a ruby glass set in one of its walls to afford film development observation; a door constituting one of the walls of said cabinet to afford access thereto; a light-box secured within said cabinet having an exterior opening to admit light thereto; a ruby glass set in one of the walls of said light-box to afford film development observation; a film carrying roller disposed within said cabinet with means for rotating the same; a base supporting said cabinet and having an extension beyond the same in one direction; a tray-removing slideable bar fitted therein; a tray pan or seat secured upon said slideable tray-bar; a bottle-case having one end and its sides secured to and forming a part of its cover, one end being hinged to said cabinet, over said base extension constituting the floor of said bottle-case for containing and carrying the developing liquids, the said cover serving as a kodak seat, also to aid in excluding light from the cabinet during the insertion and removal of the tray, for the purposes set forth.

8. In a daylight film developing apparatus; a rectangular upright cabinet; a ruby glass set in one of its walls; a door constitut-

ing one of the walls of said cabinet, to afford access thereto; a light-box within said cabinet secured to one of its walls and having an external opening to admit light; a ruby glass set in one side of said box to afford light to aid in observing the development of the film; a film carrying roller secured within said cabinet with external means for rotating the same to actuate the film; a base supporting said cabinet and extending beyond the same in one direction; a slideable tray-bar fitted in said base and having a tray-pan or seat secured upon its inner end; a bottle-case consisting of a roof hinged to said cabinet, an outer vertical end and two vertical sides secured to said roof, and combining with said roof to form a kodak seat, the said base extension forming the floor of the bottle case, which assists in excluding light from the cabinet while removing and inserting the developing liquid; a wing door pivoted by its upper edge and provided with means for externally operating the same, said door constituting a light excluding partition between the cabinet and the bottle-case to aid in excluding light from the cabinet while introducing and removing the developing liquids, substantially as described.

9. In a daylight film developing apparatus; of the class described having a rectangular upright cabinet with a base extending in one direction; a door constituting one of the walls of said cabinet, with means for opening and closing the same affording access to the cabinet; a light-excluding hood secured to said cabinet around said door and having a pair of hand-holes therein, and the boundary of said hand-holes closely contacting with the wrists while adjusting the film within the cabinet, for the purposes specified.

In testimony whereof I affix my signature in presence of two witnesses.
